(57) **CLAIM**

The ornamental design for “solar pump irrigation device,” as shown and described.

DESCRIPTION

FIG. 1 shows a perspective view of a solar pump irrigation device;

FIG. 2 shows a top view of the solar pump irrigation device of FIG. 1;

FIG. 3 shows a front view of the solar pump irrigation device of FIG. 1;

FIG. 4 shows a back view of the solar pump irrigation device of FIG. 1; and,

FIG. 5 shows a lateral view of the solar pump irrigation device of FIG. 1.
